(57) **CLAIM**

The ornamental design for an adult tricycle, as shown and described.

DESCRIPTION

FIG. 1 is a perspective view showing my new design for an adult tricycle.

FIG. 2 is a right side elevational view thereof, the left side elevational view being substantially a mirror image thereof, the only difference being the position of the pedals.

FIG. 3 is a front elevational view thereof.

FIG. 4 is a rear elevational view thereof.

FIG. 5 is a top plan view thereof.

FIG. 6 is a bottom plan view thereof; and,

FIG. 7 is a detail perspective view thereof.

The portions of the adult tricycle shown in broken lines form no part of the claimed design.
